UNITED STATES PATENT OFFICE.

ANDREW WEMPLE AND GEORGE W. SMITH, OF CHICAGO, ILLINOIS.

BAND-CUTTER AND FEEDER.

SPECIFICATION forming part of Letters Patent No. 423,582, dated March 18, 1890.

Application filed December 13, 1889. Serial No. 333,804. (No model.)

To all whom it may concern:

Be it known that we, ANDREW WEMPLE and GEORGE W. SMITH, of Chicago, in the county of Cook and State of Illinois, have invented certain new and useful Improvements in Band-Cutters and Feeders; and we do hereby declare that the following is a full, clear, and exact description thereof, reference being had to the accompanying drawings, and to the letters of reference marked thereon, which form a part of this specification.

This invention relates to improvements in grain-feeding and band-cutting devices for thrashing-machines.

The invention consists in the matters hereinafter described, and pointed out in the appended claims.

In the accompanying drawings, illustrating our invention, Figure 1 shows in central longitudinal vertical section a grain-feeding apparatus embodying our invention, supported in operative position upon a thrashing-machine, part of which latter machine is shown in side elevation in said figure. Fig. 2 is a plan view of the feeding device. Fig. 3 is an enlarged sectional view of the same, taken upon lines 3 3, Fig. 1. Fig. 4 is an enlarged detail section of the upper end of the endless-belt carrier forming part of the feeding device. Fig. 5 is an end view of a flanged roller for aiding the delivery of the bundle from the feeding device to the machine. Fig. 6 is a side view of the roller shown in Fig. 5.

As shown in said drawings, Fig. 1, A indicates a thrashing-machine, a part only of which appears in Fig. 1 of said drawings.

B is a trough composing the body or main frame of the feeding device, one end of which commonly rests upon the frame of the thrashing-machine when the carrier is in position for operation. The trough is herein shown as arranged in an inclined position; but it may be otherwise placed in practice, as found convenient or desirable. Said trough consists of a flat bottom B' and sides B², secured to the margins of the bottom and extending upwardly therefrom.

The end of the trough remote from the thrashing-machine is closed by a transverse piece or end wall B³. Said lower end of the trough may be supported in any suitable

manner from the ground. As herein shown, it is sustained by means of an axle C, having wheels C' C', said axle being attached to the lower ends of posts C² C², which are pivoted at their upper ends to the frame, the posts being held in their vertical position by means of brace-rods c c.

b b are additional side pieces attached to the sides B² of the trough at the outer end of the same, and b' is an additional end piece forming an upward extension of the cross-piece B³, said parts b b' making the trough of greater depth at the point where the bundles are deposited therein.

D is a transverse shaft extending across the trough near the discharge end of the same, and D' a similar shaft at the feed end of the trough. Said shafts are arranged in transverse slots or openings formed in the bottom B' of the trough, and the shaft D is provided with a plurality of small sprocket-wheels d d, while the shaft D' is provided with pulleys.

E E E indicate a series of carrier-belts placed over the sprocket-wheels d d and pulleys d' d' of the shafts D D'. Said carrier-belts pass around that part of the bottom of the trough which is located between the shafts D and D', and the uppersurfaces of the rollers are in the same plane with the top surface of the trough-bottom B', so that the belts rest and slide upon said bottom. The several belts are provided with a series of prongs or fingers e e, which extend upwardly from the parts of said belt which rest upon the bottom of the trough.

For the purpose of sustaining the bundles free from contact with the belts themselves longitudinal strips F F, preferably of metal, are sustained over the bottom of the trough, said metal strips coming close to the fingers e e at each side of the latter, so as to form narrow slots through which said fingers travel, as clearly shown in Figs. 2 and 3. At the upper end of the trough the strips F F are bent or curved downwardly and attached to a cross-piece B⁴, the curvature of the strips being less than that of the path of the fingers, so that said fingers e are withdrawn gradually from the bundles as said fingers are carried around the shaft B' in the movement of the belts.

As a cheap, simple, and convenient con-

struction in the trough B we make the bottom B' of the same of a series of longitudinal strips b^2 b^3 , the strips being secured together side by side, and the alternate strips b^3 being 5 thicker or of greater width vertically than the intermediate ones b^2 . In other words, the upper surfaces of the strips b^3 extend considerably above the edges of the strips b^2 . The upper surfaces of the thinner strips b^2 are arranged 10 in line with the carrier-belts, which rest and slide upon the same, while the thicker strips b^3 extend above the carrier-belts and serve to support the metal strips F, which are secured to the upper surfaces of 15 said strips b^3 and project at their edges beyond the same, so as to come close to the fingers and thereby form suitable narrow slots for the passage of said fingers.

The several longitudinal strips b^2 b^3 comprising the bottom of the trough are herein shown as secured together by means of transverse bolts b^4 b^4 ; but other connecting devices may be used in practice, as found convenient or desirable.

25 It will of course be understood that as far as the general features of the invention are concerned the trough may be constructed otherwise than in the particular manner above described; but the particular construction 30 illustrated is, as far as we know, a novel one, and, inasmuch as it possesses important advantages in affording a cheap, simple, and efficient construction in the parts, the same is herein claimed as a separate improvement.

35 Motion may be given to the carrier-belts in any convenient manner, the shaft D in the construction illustrated being provided with a pulley D², over which may be placed a suitable drive-belt for turning the shaft.

40 For the purpose of aiding the discharge of the bundle from the upper end of the feeding device a roller G is mounted in the bearings g g upon the sides B² B³ of the trough, said roller being located over the strips F F 45 a short distance above the same. Said roller G is provided with a series of obliquely-arranged ribs or flanges g' g', said ribs being V-shaped, as seen when the roller is viewed in side elevation, Fig. 6, with the apex or point 50 of the V directed forwardly, having reference to the direction of motion of the roller. The ribs or flanges thus arranged serve to open or spread the bundles, the bands of which are cut before reaching said roller, while at the 55 same time carrying forward the grain past the end of the trough and allowing it to drop into the receptacle of the thrasher. The opening or spreading of the bundles is caused by the points of angles of the flanges g' g' striking into or entering the middle part of the 60 bundle, and thereby forcing the straw outwardly and distributing it evenly across the width of the trough.

The advantage of spreading the bundle in 65 the manner described is that the straw is thereby delivered to the thrashing-machine in a flat and even layer, instead of being

thrown therein in the form of a thick bundle, as would be the case were the bundle not broken up or separated in the manner described.

For cutting the bands of the bundles as they are carried upwardly or toward the thrasher by the carrier-belts, as above described, means are provided as follows: H is a cutting knife 75 or blade mounted on the bottom of the trough conveniently at a point near the upper end of the trough. The knife or cutter H, as herein shown, is stationary and secured to the bottom of the trough, having an inclined cutting-edge, which severs the band as the bundle is carried endwise over the knife. As far as the other features of the invention are concerned, however, the knife may be a movable one, and may be positively actuated, if desired. The 80 particular knife shown is made of triangular form in side view, and is provided with flanges at its base, by which it is secured to the flat bottom of the trough by screws, bolts, or rivets; but the knife may be of other form and may 85 be secured to the trough in any other manner, as found convenient or desirable in practice. Located over or opposite the said knife H is a roller I, which is adapted to freely rotate, and which also has a bodily movement 90 toward and from the said knife. To afford said bodily movement of the roller, the latter is herein shown as mounted upon a shaft I', having bearings in arms I² I², which are pivotally connected with the trough, the arms being adapted to turn upon their pivots as the roller is moved toward or from the knife. Said roller I, in cases where it may be found necessary, may be driven by devices giving it 95 a continuous rotary movement in a direction 100 to aid the passage of the bundle beneath it. One convenient way of giving such rotary motion to the roller is shown in the accompanying drawings, in which the arms I² I² are pivotally supported upon the shaft D, and said shaft is provided with a belt-pulley J, arranged 105 in the same plane with another belt-pulley J' upon the shaft I' of the roller I, a belt J² being placed over said pulleys J and J'. In this construction the roller I is driven 110 with the same shaft D by which motion is given to the carrier-belts, thereby greatly simplifying the construction of the machine. This 115 particular construction in the device for actuating the said roller I is novel, and by reason 120 of the advantages gained thereby it is herein claimed as part of our invention. As far as 125 the general features of our invention are concerned, however, we do not wish to be limited to this particular feature of construction, inasmuch as the same general results may be obtained when the said roller I is otherwise actuated—as, for instance, by a belt-driving gear independent of the devices which give motion to the chain belts of the roller.

131 We claim as our invention—

1. A feeder or band-cutter comprising a carrier belt or belts, a knife or cutter, and a roller opposed to said knife or cutter and to

the carrier belt or belts, substantially as described.

2. A feeder and band-cutter comprising a carrier belt or belts, a knife or cutter, and a roller arranged opposite the knife or cutter and the belt and movable bodily toward and from the same, substantially as described.

3. A feeder and band-cutter comprising a carrier belt or belts provided with prongs or fingers, supporting-strips for the bundle located above the belt and forming slots for the passage of the prongs or fingers, a knife or cutter located in the path of the bundle carried by the said belt or belts, and a roller arranged opposite the knife and the said supporting-strips, substantially as described.

4. A feeder and band-cutter comprising a carrier belt or belts, a knife or cutter for severing the band, a roller arranged opposite said knife or cutter and the belt and movable bodily toward and from the same, and means of giving rotary motion to said roller, substantially as described.

5. A feeder and band-cutter comprising a carrier belt or belts, a revolving shaft provided with sprocket wheels or pulleys supporting and giving movement to said belt or belts, a knife or cutter for severing the bands, a roller arranged opposite the knife or cutter and movable bodily toward and from the same, swinging arms supporting said roller

mounted concentrically with said shaft, and belt-pulleys upon the said shaft and roller, substantially as described.

6. A feeder and band-cutter comprising a carrier belt or belts provided with prongs or fingers, stationary supporting-strips located above the belts and forming slots for the said prongs or fingers, a knife or cutter for severing the bands mounted upon one of said stationary strips, and a roller located opposite said knife or cutter and movable bodily toward and from the same, substantially as described.

7. A feeding device comprising a trough the bottom of which is composed of a series of strips of unequal vertical thickness, a plurality of carrier-belts provided with prongs and arranged to rest and travel upon the thinner strips, and supporting-strips for the bundle secured to the upper surface of the thicker strips and forming slots for the passage of said prongs or fingers, substantially as described.

In testimony that we claim the foregoing as our invention we affix our signatures in presence of two witnesses.

ANDREW WEMPLE,
GEORGE W. SMITH.
